Inventor
WILLIAM T. McCARLEY,

By Franklin D. Stash

Attorney

UNITED STATES PATENT OFFICE.

WILLIAM T. McCARLEY, OF LULING, TEXAS.

DEVICE FOR LIFTING PUSH-RODS ON FORD MOTORS.

1,395,128.

Specification of Letters Patent.

Patented Oct. 25, 1921.

Application filed September 18, 1920. Serial No. 411,278.

To all whom it may concern:

Be it known that I, WILLIAM T. McCARLEY, a citizen of the United States, residing at Luling, in the county of Caldwell and State of Texas, have invented certain new and useful Improvements in Devices for Lifting Push-Rods on Ford Motors; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of this invention is to provide an improved form of device for lifting push rods, intended more particularly for use on Ford motors, but susceptible of use, of course, on other makes of automobiles, the lifting device being used when it is desired to position the cam shaft bearing in the Ford motors.

The invention is clearly disclosed in the accompanying drawing, in which like reference characters designate corresponding parts throughout the several views. Briefly described:

Figure 1 is a fragmentary view in side elevation, of a portion of an automobile with the device of my invention in operative position;

Fig. 2 is a view in top plan of the stationary and movable jaws and the screws carried by the movable jaws for actuating the same, and showing, in section, a push-rod clamped by a pair of said jaws, and

Fig. 3 is a collective detail view, in perspective, of the member carrying the stationary jaws, and of one of the movable jaws detached.

Fig. 4 is a top plan view of the base with the jack screw shown in section.

Referring now in detail to the drawings:

1 designates a base, which may be of suitable form, in this instance comprising a plate having arcuate ends 2, 2.

Rising from the base is a screw 3, carrying a nut 4.

50 A casting 5 is formed with a centrally recessed portion 6, adapted to receive the screw 3, and is also provided with wings 7, 7 constituting stationary jaws, and having curved outer surfaces 8, 8.

55 Carried by each of said stationary jaws 7 is an ear 9, perforated, as shown at 10.

Said ear 9 is adapted to be projected into an aperture 11 in a movable jaw 12, said jaw having a curved jaw face 13. As shown in detail in Fig. 3, said jaw 12 is curved longitudinally. It is also provided with an opening 14, adapted, when the jaw is disposed on the ear 9, to register with the opening 10, a pivot pin 15 passing through said registering openings and pivotally securing the movable jaw to the stationary jaw. Each movable jaw is provided laterally with a screw threaded opening 16, through which an adjusting screw 17 passes, one end of said screw being adapted to bear upon the casting 5, as shown clearly in Fig. 2, and the other end of said screw being provided with a head, or thumb piece, 18, for convenient manipulation of the screw.

In operation, the base plate 1 is positioned, as shown in Fig. 1, between two of the push-rod guides a, the arcuate ends 2, 2 of the plate engaging the guides a, which latter have a circular exterior surface. The base-plate is thus held against horizontal movement.

The operator then turns the motor with a crank until one valve reaches its highest point on the cam shaft. He then loosens the thumb screws 17, 17 and disposes the stationary jaw-carrying member 5 on the screw 4 with the screw 3 in the recess 6, and clamps the push-rod A, that has been raised, as aforesaid, by screwing up upon the screw 17 carried by the jaw member 12, until the push-rod is clamped between the jaw face 13 and the corresponding, or adjacent, stationary jaw 7. Thereupon, the operator turns the motor again until the next valve rises to its highest point. He then swings the other movable jaw 12 toward this second raised push-rod, clamping the same as in the case of the first push-rod.

The operator then takes a wrench and turns the nut 4 to elevate the same upon 100 the screw 3, which raises the push-rods held by the coöperating jaws, as aforesaid, so that the push-rods are raised entirely off of the cam shaft B, carrying the cams b. The operator then proceeds to adjust another set of clamps to the remaining push-rods, and proceeds in the same manner as before to raise these rods off of the cam shaft. When all of the push-rods have been raised from the cam shaft, the cam shaft is 110 left free to be pulled out of the motor and a new bearing installed.

The curved face 8 on each stationary jaw facilitates application of the device, when it is desired to use the same.

As shown, each device is adapted for use 5 with two adjacent push-rods A, A.

What I claim to be new is:

1. A device for lifting valves in automobile motors, comprising a casting formed to provide two oppositely disposed rigidly 10 related jaws, a movable jaw pivotally carried by each of said stationary jaws, means for actuating said movable jaws and means to lift all of said jaw structures as an organized unit.

15 2. A device for lifting valves in automobile engines, comprising a member provided with two opposed stationary jaws, a movable jaw pivotally carried by each of said stationary jaws, and a thumb screw 20 carried by each of said movable jaws and bearing against said member for actuating said movable jaws.

3. A device for lifting valves in automobile engines, comprising a base, a screw

carried by said base and rising therefrom 25 and carrying a nut, a member provided with a recess adapted to receive said screw, and with two oppositely disposed projections constituting stationary jaws, a movable jaw pivotally carried by each of said stationary 30 jaws, and means for actuating said movable jaws to clamp two valve stems between said stationary and movable jaws.

4. A device for lifting valves in automobile engines, comprising a base, a screw 35 upstanding from the base, a nut carried upon the screw, a plate having a central aperture adapted to slide over the screw and bear upon the nut and having opposed rigidly related jaw faces, movable jaws 40 pivoted to the plate, and means for applying stress to the movable jaws to clamp an article between the movable jaws and the rigid jaw faces.

In testimony whereof I hereunto affix my 45 signature.

WILLIAM T. McCARLEY.
